UNITED STATES PATENT OFFICE

130,655

DESIGN FOR A WATCH BRACELET OR THE LIKE

Karl C. Augenstein, Cranston, R. I., assignor to
Edwin F. M. Speidel, Cranston, R. I.

Application July 21, 1941, Serial No. 102,333

Term of patent 14 years

To all whom it may concern:

Be it known that I, Karl C. Augenstein, a citizen of the United States, residing at Cranston, in the county of Providence and State of Rhode Island, have invented a new, original, and ornamental Design for a Watch Bracelet or the like, of which the following is a specification, reference being had to the accompanying drawing, forming part thereof.

In the drawing,

Fig. 1 is a plan view of a watch bracelet showing my new design, the links of the bracelet being retracted;

Fig. 2 is an edge view of the bracelet;

Fig. 3 is a bottom view of the bracelet; and
Fig. 4 is a fragmentary plan view of the bracelet links in expanded position.

The broken lines of the figures are used to avoid repetition of the drawing of individual links of the bracelet. It will be understood that the bracelet comprises a series of similarly shaped top and bottom links respectively, extending from end to end thereof.

I claim:

The ornamental design for a watch bracelet or the like, substantially as shown and described.

KARL C. AUGENSTEIN.
